(57) **CLAIM**

The ornamental design for a curved pole with lighting fixture, as shown and described.

DESCRIPTION

FIG. 1 is a perspective view of a curved pole with lighting fixture.

FIG. 2 is a front elevation view of the curved pole with lighting fixture of FIG. 1, a back elevation view being a mirror image.

FIG. 3 is a left side elevation view of the curved pole with lighting fixture of FIG. 1.

FIG. 4 is a right side elevation view of the curved pole with lighting fixture of FIG. 1.

FIG. 5 is a top plan view of the curved pole with lighting fixture of FIG. 1; and,

FIG. 6 is a bottom plan view of the curved pole with lighting fixture of FIG. 1.

The broken lines shown on the drawings are for illustrative purposes only and form no part of the claimed design.
